The ornamental design of a blender whipping blade, as shown and described.

DESCRIPTION

FIG. 1 is a perspective view of a blender whipping blade showing our new design;

FIG. 2 is a top view thereof;

FIG. 3 is a bottom view thereof;

FIG. 4 is a side view thereof;

FIG. 5 is a perspective view of the blender whipping blade connected with a blending container; and,

FIG. 6 is a top view of the blender whipping blade connected with the blending container.

The broken lines in the figures are included for the purpose of illustrating portions of a blender whipping blade and blending container and form no part of the claimed design.
